UNITED STATES PATENT OFFICE.

ALBERT N. WOODRUFF, OF NEW YORK, N. Y.

COPY-HOLDING DEVICE.

1,414,389.

Specification of Letters Patent.

Patented May 2, 1922.

Application filed October 9, 1920. Serial No. 415,712.

To all whom it may concern:

Be it known that I, ALBERT N. WOODRUFF, a citizen of the United States, and a resident of the city of New York, borough of Manhattan, in the county and State of New York, have invented a new and Improved Copy-Holding Device, of which the following is a full, clear, and exact description.

The present invention relates to new and useful improvements in office furniture, and it pertains more particularly to a copy-holding device.

It is one of the objects of the invention to provide a device which will support a manuscript to be copies in a convenient position for the operator thereof.

It is a further object of the invention to provide in combination with the copy-holder, a line-spacing mechanism.

20 It is a further object of the invention to provide means by which the line-spacing mechanism may be operated.

It is a further object of the invention to provide a device which is simple in construction and economical in cost of manufacture.

It is a further object of the invention to provide a device which may be folded when not in use in such a manner as to occupy but little space.

30 With the above and other objects in view, reference is had to the accompanying drawings, in which

Figure 1 is a top plan view of a copy holder constructed in accordance with the present invention;

Figure 2 is a bottom plan view thereof;

Figure 3 is a view in side elevation;

Figure 4 is a longitudinal sectional view, and

40 Figure 5 is a detail transverse sectional view.

Referring more particularly to the drawings, the device comprises a supporting bed 10 and a base member 11. The supporting bed 10 is formed preferably from sheet metal and has its side edges bent backwardly upon the under side of the body portion as indicated by 12, said side edges being spaced from the bed to provide guideways, the purpose of which will be hereinafter more specifically described.

The base member 11 is formed preferably from wire and is substantially U-shaped in form, the base 13 of the U-shaped member

lying in a plane above the base proper. The 55 free ends 14 of the legs of the U-shaped member are angularly disposed as indicated at 15, for a purpose to be hereinafter described. Pivottally secured to the base 13 of the U-shaped member are links 16, and said links 16 are arranged in spaced relation to each other.

Pivottally mounted in ears 17 which project from the upper end of the supporting bed 10, is a U-shaped member 18, and the 65 links 16 are coiled about the base of the member 18 as indicated by the reference character 19 in Fig. 2. One of these links 16 is provided with an extended end bent in the form of an operating handle 20, by means 70 of which one of the links 16 may be rocked about its pivotal point on the U-shaped member 18 as will be hereinafter more fully described.

As more clearly shown in Fig. 2, the rear 75 face of the supporting bed 10 is provided with spaced guide members 21, near its upper end, and near its lower end by a single guide member 22.

The reference character 23 designates a 80 corrugated or otherwise roughened bar, and said bar is provided with oppositely disposed wings 24, adapted to engage the pairs of guide members 21 in order that the bar may be reciprocated upon the rear face of the 85 supporting bed 10. As more clearly shown in Fig. 5, this roughened bar 23 has a flat side which slides in engagement with the rear face of the supporting bed 10. Near its lower end the bar 23 is provided with a wing 90 25, adapted to slide beneath the guide member 22, and upon its side opposite to the wing 25, is a wing 26 having an upstanding lug 27. Connected to the upstanding lug 27, of the wing 26, is a coil spring 28, and said coil 95 spring 28 is secured to one of the wings 50 as indicated by the reference character 29. By this construction, it will be apparent that as the bar 23 is reciprocated, the coil spring 28 will be placed under tension and will 100 serve to return the bar 23 to normal position upon release of the force by which it is reciprocated.

In order that the bar 23 may be reciprocated, an operating lever 30 is employed, and said operating lever 30 is pivotally mounted as at 31, in a yoke 32, pivotally mounted as at 33 upon the angularly disposed ends of

the legs of the base member 11. This yoke member 32 is provided with an upstanding lug 34, and engaging said upstanding lug 34 is the downwardly bent end 35 of a hook member 36. The opposite end 37 of this hook member is bent downwardly and rigidly secured as at 38 to the bar 23. The lower end of the operating lever 30 is provided with an angularly disposed portion 39 adapted to engage the base of the upstanding lug 34 of the yoke member 32. By this construction it will be seen that the operating member is free to move about its pivotal point 31 when rocked forwardly as shown in dotted lines in Fig. 3, but as shown by dotted lines in said figure, when the operating lever is pulled rearwardly, the angularly disposed extension 39 will engage the base of the upstanding lug 34 and will cause a rocking of the lug about its pivotal point 33 and cause a reciprocation of the bar 23.

In order to vary the length of stroke of the reciprocations of the bar 23, the wedge-shaped member 40 is provided, and said wedge-shaped member 40 is slidably mounted upon an upstanding lug 41, as more clearly shown in Figs. 1 and 4. By moving said wedge-shaped member 40 transversely of the supporting bed 10, it will be apparent that the downwardly bent end 37 of the member 36 will engage said wedge-shaped member and limit its rearward movement. By this arrangement, the stroke of the bar 23 is varied.

35 Mounted on the rear face of the supporting bed 10 and having sliding movement in the guideway 12, is a carriage 50. Pivotally mounted in this carriage, is a line marker 51, the ends of said line marker 51 being bent around the supporting bed and pivotally secured to the carriage as indicated by the reference character 51. One of the legs of the line marker 51 is extended downwardly as indicated by the reference character 53, and pivotally secured to said downwardly bent end is a pivoted lever 54 cut out to provide a shoulder 55. Pivotally mounted on the carriage 50, as at 56, in ears 57, is a pawl 58, and said pawl is provided 40 with a cut-out portion 59, through which the reduced end 60 of the pivoted lever 54 passes. The end 61 of this pawl is adapted to engage the roughened portion of the reciprocating bar 23 as more clearly shown in Fig. 4, and the end 61 of said bar is maintained in engagement with the roughened portion of the bar 23 by a coil spring 62, one end of which is secured to the pawl 58 opposite the end 61, the other end being secured as at 64 to the carriage 50.

Secured to the upper end of the supporting bed 10, is a U-shaped sheet metal member 70, which forms a clamp by means of which the manuscript copy is retained in 55 position on the bed 10. The several leaves

of a book or the like are adapted to be passed between the members of the clamp as shown in Fig. 3.

The device operates in the following manner:

With a book or other copy mounted on the supporting bed 10, the line marker 51 is positioned at the first line of writing on the manuscript copy near the upper end of the sheet. In order to accomplish this, the line marker 51 is grasped and rocked about its pivotal points 52. This operation causes a reciprocation of the lever 54 through the medium of the downwardly bent portion 53 of the line marker, until the shoulder 55 of said lever engages the lower end of the pawl 58, which action rocks the pawl out of engagement with the roughened portion of the bar 23 and permits of free movement of the carriage with respect to the supporting bed in order that the line marker 51 may be properly positioned. Upon release of the line marker 51, the same returns to the full-line position shown in Fig. 4, under the influence of a spring 80, and this movement of the line marker 51 permits the pawl 58 to be moved about its pivotal point until its end 61 engages the roughened portion of the bar 23, it being understood that the spring 62 serves to rock the pawl 58 as heretofore stated.

Assuming now that the operating lever 30 be rocked about its pivotal point 31 until its angularly disposed end 39 engages the base of the member 34 of the yoke 32. Upon the completion of further pressure of the operating lever 30, the yoke 32 will be rocked about its pivotal point and through the medium of the hook member 36, will reciprocate the roughened bar 23. As the roughened bar 23 is reciprocated, the carriage, owing to the engagement of the end 61 of the pawl 58, will be moved relatively to the supporting bed 10, and the distance of movement of said carriage 50 will be regulated by the positioning of the wedge-shaped member 40.

From the foregoing it will be apparent that the present invention provides means whereby a manuscript copy may be supported in convenient position for copying, and, at the same time, a simple and novel mechanism for operating a line marker has been devised. Furthermore, the invention provides a device of this character which may be folded into a comparatively small space, together with new and novel means for operating the carriage spacing mechanism.

I claim:

1. In a device of the character described, a base, a writing bed, a carriage mounted upon the writing bed, a pivoted pawl mounted upon the carriage, manually operated means adapted for engagement with the pawl to move the carriage in one direction,

a line indicator, and means operated by the line indicator for disengaging the pawl from the manually operated means to permit of a free movement of the carriage in either direction.

5 2. In a device of the character described, a base, a writing bed, a carriage mounted on the bed, means for reciprocating said carriage in one direction and preventing its 10 movement in the opposite direction, a line indicator, and means associated with and operated upon movement of the line indicator for disconnecting the carriage-operating means to permit of a free movement of 15 the carriage in either direction.

3. In a device of the character described, a base, a writing bed carried by the base and foldable with respect thereto, a carriage mounted for sliding movement on the writing bed, means for reciprocating said carriage in one direction and preventing reciprocating movement thereof in the opposite 20 direction, a line indicator pivotally mounted

on the carriage, and means associated with and operated upon pivotal movement of the 25 line indicator for disconnecting the carriage-reciprocating means to permit of a free movement of the carriage in either direction.

4. In a device of the character described, 30 a base, a writing bed, a carriage mounted on the bed, means for reciprocating the said carriage in one direction and preventing its movement in the opposite direction, said means comprising a pivoted pawl mounted 35 on the carriage, and a reciprocating rack bar carried by the bed and adapted to be engaged by said pawl, a line indicator, and means carried by the line indicator and engaging said pawl whereby upon movement 40 of the line indicator the pawl will be disengaged from the rack to permit of free movement of the carriage in either direction on the bed.

ALBERT N. WOODRUFF.
